UNITED STATES PATENT OFFICE.

PETER DARABOS, OF OAKDALE, PENNSYLVANIA.

SAFETY DEVICE FOR MINES.

984,355.

Specification of Letters Patent.

Patented Feb. 14, 1911.

Application filed December 7, 1910. Serial No. 596,121.

To all whom it may concern:

Be it known that I, PETER DARABOS, a subject of the King of Hungary, residing at Oakdale, in the county of Allegheny and 5 State of Pennsylvania, have invented certain new and useful Improvements in Safety Devices for Mines, of which the following is a specification, reference being had therein to the accompanying drawing.

10 This invention relates to a safety device for mines, quarries, and underground workings, and the primary object of the invention is the provision of simple and effective means for supplying fresh air to a mine, par- 15 ticularly when explosions occur.

Another object of the invention is to provide a mine with a ventilating system that insures perfect safety of the miners, and with stores or compartments containing first 20 aid to imprisoned miners.

I attain the above objects by a device that will be hereinafter specifically described and then claimed, and reference will now be had to the drawings, wherein:

25 Figure 1 is a longitudinal sectional view of a portion of a mine equipped with the device. Fig. 2 is a horizontal sectional view of the same looking toward the roof of the mine, and Fig. 3 is a longitudinal sectional 30 view of one of the stores of the mine.

The reference numeral 1 denotes an elevator shaft leading from the surface of the ground to a mine entry 2 having communicating halls or rooms 3.

35 4 denotes an air shaft communicating with the entry 2 adjacent to the elevator shaft 1. The upper end of the air shaft 4 is closed by a hood 5 and this hood is in communication with a fan house 6 through the medium of an opening 7. In the fan house is located a 40 fan casing 8 containing a revoluble fan 9 adapted to be operated by a motor 10 or other source of power, the fan 9 receiving air through an opening 11 from the exterior of 45 the house 6 and delivering the air through the opening 7 into the shaft 4, the entry 2, and the rooms 3 thereof. The opening 7 can be closed by a flap door 12 normally supported in an open position by a ledge 13 arranged at the bottom edge of the opening 7, said flap door extending into the hood 5. The top of the hood 5 is provided with an opening 14 and this opening is normally closed by a flap door 15 hinged, as at 16, to 50 the top of the hood whereby the door can be swung upwardly to an open position.

17 denotes a pipe arranged along the roof of the entry 2 and the rooms 3, and this pipe is provided with equally spaced perforated heads 18. The pipe 17 has a tee 19 connected 60 to a vertical pipe 20 extending upwardly in the air shaft 4 adjacent to one of the side walls thereof. The upper end of the pipe 20 is connected to a funnel-shaped member 21 in communication with the fan casing 8, and 65 in the funnel-shaped member 21 is located a slide valve 22 normally held in a closed position by a rod 23 pivotally connected to the lower end 24 of an operating lever 25, said lever extending upwardly through the floor 70 of the fan house 10 and being pivotally supported at the floor line by bearings 26.

The mine throughout can be lighted by incandescent electric lamps 27 and at suitable points or stations within the mine 75 stores are located comprising boxes or tanks 28 containing water 29 and sponges 30, the sponges being separated from the water 29 by a partition 31 located within the box. Easy access is had to the water 29 and the 80 sponges 30 through the medium of openings 32 in the top of the box, and said openings being normally closed by hinged lids 33. Besides water and sponges other necessary supplies adapted to render first aid to 85 entombed miners can be maintained for an object that will presently appear.

The fan 9 is operated to supply air to the miners or workmen within the entry 2 and the communicating rooms and should an 90 explosion occur, the up-draft or escape of the gases and fumes through the air shaft 4 immediately closes the flap door 12, thus preventing the fan 9 from being injured, and opens the flap door 15 allowing the 95 fumes and gases to escape. When an explosion occurs it is only necessary for the attendant of the fan 9 to operate the lever 25 and open the slide valve 22. The air within the fan casing 8 will then be driven by the 100 fan through the member 21 into the pipes 20 and 17, the air being disseminated throughout the entry and the communicating rooms by the perforated heads 18. Should the force of the explosion be such as to 105 cause a cave-in and prevent the escape of the miners, the entombed miners can seek one of the stores, obtain water, sponges, and such other supplies that may be in store, the sponges when moistened and held to the 110 nose immediately relieving the miners from such gases and fumes as may have been in-

haled during the interval of the explosion and the time of locating the stores.

It is thought that the operation and utility of the device for saving the lives of miners will be apparent without further description, and while in the drawings there is illustrated a preferred embodiment of the invention, it is to be understood that the structural elements thereof are susceptible 10 to such changes as fall within the scope of the appended claims.

What I claim, is:

1. In a safety device for mines, the combination with a mine having an entry, 15 rooms, and an air shaft, of a hood located over said air shaft, a fan casing in communication with said hood, a revolute fan located in said casing and adapted to supply air to said air shaft, a flap door adapted 20 to control the communication between said fan casing and said hood and extending outwardly into said hood, a flap door carried by the top of said hood and adapted to be opened by an up-draft within said shaft, 25 an air supply pipe located within said mine, a pipe establishing communication between said air supply pipe and said fan casing, and a slide valve adapted to control the supply of air from said fan casing to said 30 air supply pipe.

2. In a safety device for mines, the combination with a mine having an entry, rooms, and an air shaft, of a hood located 35 over said air shaft, a fan casing in communication with said hood, a revolute fan located in said casing and adapted to supply air to said air shaft, a flap door adapted to control the communication between said fan casing and said hood and extending 40 outwardly into said hood, a flap door car-

ried by the top of said hood and adapted to be opened by an up-draft within said shaft, an air supply pipe located within said mine, a pipe establishing communication between said air supply pipe and said fan casing, a 45 slide valve adapted to control the supply of air from said fan casing to said air supply pipe, and perforated heads carried by said air supply pipe within said mine.

3. In a safety device for mines, the combination with a mine having an entry, rooms, and an air shaft, of a hood located over said air shaft, a fan casing in communication with said hood, a revolute fan located in said casing and adapted to supply air to said air shaft, a flap door adapted to control the communication between said fan casing and said hood and extending outwardly into said hood and adapted to be closed by an up-draft in said shaft, a flap 60 door carried by the top of said hood and adapted to be opened by an up-draft within said shaft, an air supply pipe located within said mine, a pipe connecting with said air supply pipe and extending upwardly in said air shaft, a funnel-shaped member connecting the upper end of said pipe with said fan casing, a slide valve located in said member and controlling the communication between said fan casing and 65 said air supply pipe, and perforated heads carried by said air supply pipe within said mine.

In testimony whereof I affix my signature in the presence of two witnesses.

PETER DARABOS.
